HERMETICALLY SEALED TRIBOELECTRIC GENERATOR AND IMPACT SENSING UNIT FOR A FUZE

Renato Bianchi, Laurel, Md., assignor to the United States of America as represented by the Secretary of the Navy

Application May 6, 1952, Serial No. 286,411

9 Claims. (Cl. 102—70.2)

(Granted under Title 35, U. S. Code (1952), sec. 266)

This invention relates to an electric controlled projectile fuze and more particularly to a generating device for use in the base or nose of the fuze for generating electrical energy during the free flight of the projectile toward a target sufficient to function the fuze and explode the projectile upon impact of the projectile with a target.

The development of electric fuzes for projectiles, especially those employing electrically operated devices, has heretofore been impeded by lack of a satisfactory source of electric operating current to function the electrical devices therein particularly after the projectile has been stored over a long period of time under adverse weather conditions.

The present invention provides means whereby an adequate source of current is developed within the projectile during the free flight of the projectile toward the target and thus assuring proper functioning of the device and explosion of the projectile upon impact of the projectile with a target notwithstanding the fact that the projectile may have been stored over a long period of time under adverse weather conditions. Furthermore, the present invention provides a device for use in an electric fuze having the essential characteristics of safety during handling and transportation and which is sufficiently small in size such that the device may be used in the type of projectiles now used by the armed forces without increasing the normal size or weight of such projectiles.

The present invention contemplates the use of a new and improved generating device for a fuze which is in the form of a triboelectric or dust type electrostatic generator and in which means controlled by the spin of the projectile charge a storage device at a slow rate with electrical energy as the projectile travels along a trajectory and in which means are provided for causing the spin controlled means to discharge the energy instantaneously from the storage device through an electroresponsive detonator upon impact of the projectile with the target and in an amount sufficient to cause the detonator to be fired in response thereto and thus explode the projectile.

An object of the invention is the provision of a new and improved generating device for use in a projectile for generating electrical energy in response to rotation of the projectile during the free flight of the projectile toward a target.

Another object is the provision of a generator device in which means are provided for transferring the energy generated therein through an electroresponsive detonator to a storage device at a rate insufficient to fire the detonator.

Another object is to provide a hermetically sealed dust type generating device in which means are provided for charging a storage device at a slow rate in one direction as the projectile spins along its trajectory and in which means are provided for causing the storage device to discharge instantaneously in the reverse direction at a rate sufficient to fire an electroresponsive detonator upon impact of the projectile with a target.

2

A further object of the invention is to provide a new and improved electric fuze for a projectile in which means are provided for delaying the arming of the fuze until the projectile has been fired from a gun and the speed of rotation of the projectile after being fired therefrom has reached a predetermined value.

An additional object resides in the provision of a dust type electrostatic generator for a projectile fuze which also functions as an impact responsive switch for controlling firing of the fuze.

Still another object is to provide a dust type electrostatic generator for a projectile fuze having provisions for releasing the dust particles in response to predetermined forces attendant upon the firing of the projectile from the gun and having additional provisions for new and improved distribution and centrifugal displacement of the dust particles in response to the spin of the projectile in flight.

Other objects and many of the attended advantages of this invention will be readily appreciated as the same becomes better understood by reference to the following detailed description when considered in connection with the accompanying drawings wherein:

Fig. 1 is a central longitudinal sectional view of the device of the present invention according to a preferred embodiment thereof;

Fig. 2 is a diagrammatic representation of an electrical circuit employed with the device of Fig. 1;

Fig. 3 is a central longitudinal sectional view of an alternate arrangement of the device of Fig. 1;

Fig. 4 is a diagrammatic representation of an electrical circuit employed with the device of Fig. 3; and

Fig. 5 is a central longitudinal sectional view of another arrangement of the device of Fig. 1.

Referring now to the accompanying drawings in which like reference characters designate corresponding parts throughout the several views and more particularly to Fig. 1 thereof, the numeral 10 generally designates the new and improved triboelectric generator comprising a hermetically sealed casing 11 composed of any material suitable for the purpose such, for example, as "Bakelite," "Lucite," or the like, and having a chamber 12 formed therein.

Disposed within the chamber 12 in engagement with the wall defining the chamber is a cup-shaped member or collecting cylinder 13 composed of any material suitable for the purpose such, for example, as copper and comprising a cylindrical wall 14, a bottom or connecting wall 15, and a flanged portion 16 adapted to collapse in response to impact of the projectile as the projectile strikes the target.

An inverted cup-shaped member or cylindrical grid generally indicated by the numeral 17 and composed of copper screen or the like foraminous material is disposed within chamber 12 and the member 13. The grid 17 comprises a cylindrical wall 18 in spaced concentric relation with respect to the wall 14 and a bottom or connection wall 19 secured to the casing as at 21 in any suitable manner and normally spaced from the flanged portion 16, it being noted that the end portion 22 of wall 18 is spaced from the wall 15.

Secured electrically to the walls 15 and 19 respectively in any suitable manner is a pair of terminals 23 and 24 thereby to provide external electrical connections for the members 13 and 17 the purpose of which will become more clearly apparent as the description proceeds.

Disposed within the grid 17 and secured thereto as by a resilient ring 25 is a frangible container 26, the container having a quantity of powdered material 27 therein such, for example, as talcum powder. It will be understood, however, that the container is composed of mate-

rial of sufficient strength to withstand the usual shock forces to which the projectile is subjected during handling and transportation but will readily rupture or fracture and release the dust therein in response to the high velocity at which the projectile rotates caused by the driving band on the projectile engaged by the rifling of the gun as the projectile is propelled outwardly therefrom by the firing of the explosive charge disposed within the shell of the projectile. As the projectile rotates, and in response to centrifugal force the powder is forced at a high velocity through the openings in wall 18 of grid 17 and collects on the cylindrical wall 14 of member 13 and thus by the aforesaid arrangement and during the action of the powder caused by the rotation of the projectile at a high speed a static charge is collected on members 13 and 17.

Referring to the circuit arrangement of Fig. 2 it will be noted that an electroresponsive detonator or primer 28 and condenser 29 are connected in series with the generator 16 by way of suitable conductors connected to terminals 23 and 24 and thus it will be apparent that the condenser is charged by the generator at a relatively slow rate through the detonator 28 in response to rotation of the projectile during the free flight of the projectile toward the target, it being understood, however, that during this charging cycle or transfer of energy, the rate is insufficient to fire the detonator. However, upon impact of the projectile with a target the flange 16 on member 13 collapses in response thereto whereupon the flange 16 is forcibly driven into engagement with the wall 19 of member 17 thereby shorting members 13 and 17. When this occurs, the energy stored within condenser 29 in the aforesaid manner is instantaneously discharged through detonator 28 in an amount sufficient to fire the detonator thereby exploding the projectile.

The device 10' of Fig. 3 is particularly adapted for use in a base fuze and is similar to the structure shown on Fig. 1, except that the flange 16 has been deleted from the collecting cylinder 13' and in lieu thereof an inertia responsive element generally indicated by the reference character 31 is employed in connection with an additional contact element 32 insulated from the wall 15 by a sleeve 33 composed of suitable insulating material.

The element 31 comprises a pair of resilient arms 34 secured electrically to the wall 15 of member 13' as at 35, and extending outwardly therefrom in opposite directions, the arms having weighted contact elements 36-37 formed thereon and normally out of engagement respectively with the terminal 32 and end portion 22 of the cylindrical wall 18 of grid 17. The arms 34 are adapted to be moved first in one direction and thereafter in the reverse direction in response to set back and set forward forces respectively as will be hereinafter more fully set forth.

Referring now to the circuit arrangement of Fig. 4 for a more complete understanding of the operation of the base fuze of Fig. 3 it will be noted that in this arrangement the detonator 28 and condenser 29 are shorted when the element 36 moves into engagement with the terminal 32 in response to set back force produced as the projectile is fired from a gun and will remain shorted until the set back force has decreased sufficiently to permit the arms 34 to move to their normal position. When this occurs and in response to the rotation of the projectile as heretofore set forth, the condenser 29 will be charged. However, on impact of the projectile with the target the inertia responsive device is moved forwardly in response to the set forward force received thereby whereupon the elements 36-37 on arms 34 move into engagement with the member 17 shorting cylinders 13' and 17 and thus the condenser 29 instantaneously discharges in an amount sufficient to fire the detonator.

In the arrangement of Fig. 5 an additional grid member 38 is employed for producing a uniform distribution of the dust and thereby increasing the output of the generator and comprises a conical grid member 39 se-

cured to the casing in any suitable manner and extending into a second grid member 41 which is substantially enclosed by a collecting cylinder 42 similar to the arrangements of Figs. 1 and 3. A frangible dust container or ball 43 composed of any material suitable for the purpose such, for example, as glass or the like is disposed at one end of the member 38 and is enclosed by a collapsible bellows 49 and thus when the bellows is collapsed in response to a sudden shock or pressure applied thereto 10 in any suitable manner as the projectile is fired from a gun, the ball is crushed thereby and the dust is released therefrom. When this occurs and in response to the high speed of rotation of the projectile, the particles of dust or powder will be forced at a high velocity along the 15 conical wall of member 38 and dispersed through the openings therein at a high rate of speed, it being understood, however, that some of the dust particles will travel upwardly along the conical wall of the member 38 and be dispersed at the upper open end thereof. The aforesaid particles thereafter are forced through grid 41 and collect on the cylindrical wall of member 42 whereupon a static charge is collected on grid 41 and cylinder 42. It will be noted in the arrangement of Fig. 5, a terminal 45 is secured to the element 41 and a terminal 46 is 20 secured to the element 42 for providing an external electrical connection thereto, the device being adapted to function in the same manner as the device of Fig. 1 when the element 41 is forced into engagement with a flange 47 on element 42 upon impact of the projectile with a 25 target.

Briefly stated in summary, the present invention provides a fuze arrangement for a projectile comprising a triboelectric generator hermetically sealed within a suitable casing adapted to function and produce electrical energy 30 in response to rotation of the projectile during the free flight of the projectile along its trajectory whereupon a storage device is charged at a slot rate through an electro-responsive detonator, the rate at which the energy is transferred to the storage device being insufficient to fire the detonator. However, upon impact of the projectile with a target the storage device is instantaneously 35 discharged through the detonator in an amount sufficient to fire the detonator and thus causing the projectile to explode. The amount of the charge depends upon the speed of rotation of the projectile, the particle size of the dust and the number of dust particles forced through the grid and the velocity at which the particles pass from the grid and collect on the outer cylinder.

Obviously many modifications and variations of the 40 invention are possible in the light of the above teachings. It is therefore to be understood that within the scope of the appended claims the invention may be practiced otherwise than as specifically described.

The invention described herein may be manufactured 45 and used by or for the Government of the United States of America for governmental purposes without the payment of any royalties thereon or therefor.

What is claimed as new and desired to be secured by Letters Patent of the United States is:

1. In an electric fuzed projectile of the character disclosed, the combination of an energy storage device, an electroresponsive detonator series coupled to said storage device, a triboelectric energy generating device series coupled to said detonator and storage device for slowly charging said storage device through said detonator at a rate insufficient to fire the detonator as the generating device is rotated, said storage device being adapted to quickly discharge the energy stored therein through the detonator at a rate sufficient to fire the detonator in response to impact of the projectile with a target, and means on said generator for causing said discharge of the energy in response to said impact.
2. An electric fuze of the character disclosed for use in a projectile comprising, in combination, an energy storage device, an electroresponsive detonator, a gen-

erator connected in series with said detonator and storage device and actuated in response to rotation of said projectile, said generator including a grid for collecting an electrostatic charge thereby charging said storage device through said detonator at a rate insufficient to fire the detonator as the generator is rotated, and impact responsive means on said generator in close spaced adjacency to said grid and electrically connected to said storage device for engaging said grid thereby causing discharge of said storage device through said detonator at a rate sufficient to fire the detonator upon impact of the projectile with a target.

3. In an electric fuze of the character disclosed for use in a projectile, in combination, an energy storage device, an electroresponsive detonator, a hermetically sealed triboelectric generator connected in series with said detonator and storage device and comprising a grid member disposed within said generator, a quantity of dust, means for sealing said dust within said generator and for releasing the dust for passage through said grid member in response to centrifugal force as the projectile spins and means including said grid member for generating electrical energy as the dust is forced therethrough in response to said force, circuit means for transferring said electrical energy to the storage device through said detonator at a rate insufficient to fire the detonator during rotation of the generator and for discharging said energy from said storage device through said detonator at a rate sufficient to fire the detonator upon actuation of the circuit means in response to impact of the projectile with a target, and means responsive to said impact for actuating said circuit means and causing the energy to be discharged from said storage device.

4. In an electric fuze of the character disclosed for use in a projectile, comprising, in combination, a casing, a condenser, an electroresponsive detonator, a generator hermetically sealed within the casing, a grid member disposed within said casing, a frangible container disposed within said grid and secured thereto, a quantity of powder disposed within said frangible container and released therefrom through said grid as the frangible container is ruptured in response to centrifugal force, means including said grid member for generating electrical energy as the powder is forced therethrough into engagement with said last named means in response to said force, circuit means for transferring said energy to the condenser through the detonator at a rate insufficient to fire the detonator during rotation of the generator and for discharging the energy from the condenser through the detonator at a rate sufficient to fire the detonator when the circuit means is actuated in response to the impact of the projectile with a target, and means on said generator for actuating said circuit means and causing the energy to be discharged from the condenser in response to said impact.

5. In an electric fuze of the character disclosed for use in a projectile, comprising, in combination, a hermetically sealed casing, a condenser, an electroresponsive detonator, a generator disposed within the casing and comprising an outer cylindrical member and an inner cylindrical grid member disposed within and substantially enclosed by said outer member, a frangible container disposed within said grid member and secured thereto, a quantity of powder disposed within said container and released therefrom as the container is ruptured in response to centrifugal force applied thereto, said grid member and outer cylindrical member being adapted to generate electrical energy as the powder is forced through the grid member and collected on the outer cylindrical member in response to rotation of said generator, and circuit means connecting said outer and inner members to said condenser and said detonator for transferring said energy to the condenser through said detonator at a rate insufficient to fire the detonator dur-

ing rotation of the generator and for discharging the energy from the condenser through the detonator at a rate sufficient to fire the detonator as the outer member is forcibly driven into engagement with said inner member in response to impact of the projectile with a target.

5 6. An electric fuze of the character disclosed for use in a projectile and comprising a condenser, a triboelectric generator comprising a frangible container having a quantity of powder therein and rupturing in response to rotation of the projectile during flight for charging said condenser, an electroresponsive detonator, and circuit means comprising a path for discharging said condenser through the detonator at a rate sufficient to fire the detonator as the projectile strikes a target.

10 7. An electric fuze of the character disclosed for use in a projectile comprising a casing, a generator hermetically sealed within said casing and having inner and outer cylindrical members secured thereto, said inner member having a plurality of apertures formed therein, a frangible container disposed within and secured to said inner container, a quantity of powder disposed within said container and released therefrom as the container is ruptured in response to centrifugal force applied thereto for charging said inner and outer cylindrical members with electrical energy as the powder is forced through said apertures and collected on the outer cylindrical member in response to rotation of the generator, and an electroresponsive detonator and a condenser connected in a series circuit with the generator, said generator charging said

20 25 30 35 40 45 50 55 60 65 70 condenser through said detonator at a rate insufficient to fire said detonator, said circuit comprising a discharge path from the condenser and including said inner and outer members for discharging said condenser through the detonator at a rate sufficient to fire the detonator as the outer cylindrical member is driven into engagement with said inner cylindrical member in response to impact of the projectile with a target.

8. A triboelectric generator comprising a hermetically sealed casing, a cylindrical member disposed within and secured to said casing, a pair of perforated cylinders disposed within said cylindrical member in coaxial spaced relation with respect thereto and with respect to each other, a frangible container disposed within the inner one of said cylinders, pressure responsive means enclosing said container for fracturing the container as said pressure responsive means is forcibly driven into engagement therewith in response to a sudden shock received thereby, a quantity of powder arranged with the container and released therefrom as the container is fractured thereby charging one of said perforated cylinders and the cylindrical member with a static charge as the powder is forced through said pair of perforated cylinders and collected on the cylindrical member in response to rotation of the generator.

9. In a projectile or the like, a device for generating electrical energy in response to rotation thereof comprising a hermetically sealed casing, a cylindrical member disposed within and secured to said casing, a cylindrical grid disposed within and spaced from said cylindrical member, a frangible container arranged within and secured to said grid, a quantity of powder disposed within said container and released therefrom as the container is ruptured by the force applied thereto in response to firing of said projectile, whereby electrical energy is generated between said cylindrical member and grid as the powder is forcibly ejected outwardly through the grid and collected on the cylindrical member in response to rotation of said projectile.
